OF TONAWANDA, NEW YORK

LOCK-REPLACING UNIT

Application filed November 15, 1927. Serial No. 233,434.

This invention relates to a device for replacing locks in furniture constructions, which is particularly adapted to finish a furniture construction where provision is made for using a lock, and where it is desired to omit the lock.

In the manufacture of various types of furniture it is desirable to equip the drawers, or closures for filing compartments, with locks so the files therein may be made inaccessible to unauthorized persons. In the construction of office furniture for large establishments for instance, it is frequently desired that a group of such furniture for the use of executives and certain clerks be equipped with locks, while another group of such furniture for the use of clerks have the locks omitted. This necessitates a change in the construction of the furniture and usually requires two types of constructions, one providing the locks and the other omitting them. In the construction of metal furniture this adds to the cost of the furniture, especially where it is made from die-shaped sheet material, because it requires two sets of dies for making certain portions of the furniture with the variations necessary to provide the lock in one case and omit it in the other.

This invention is designed to overcome this disadvantage in the making of furniture or other similar constructions, to eliminate the necessity for two sets of dies for making similar parts or the equivalent operation and to reduce the cost of manufacture of the furniture.

The invention comprehends the provision of furniture constructions made for equipment with locks of the desired type, which are additionally provided with suitable elements to replace the lock in the form of filler members which simulate the outward appearance of the locks, and provide the proper appearance and finish on the outside of the furniture which it normally has when provided with the locks.

The invention provides a construction in which portions of the lock supporting elements are employed in connection with a retaining means for the filler member, in

order that the lock mechanism may be readily dispensed with and a filler member having an outward appearance similar to the lock conveniently clamped in place of the lock, and thereby provide a properly finished furniture construction. 55

The invention includes numerous other objects which reside in the special construction and association of the several parts in combination with the furniture construction which are pointed out in detail in the following description and claims, directed to the preferred construction, it being understood however, that various changes may be made in the construction and association of these parts without departing from the spirit and scope of the invention as herein set forth. 60 65

In the drawing forming part of this application,

Fig. 1 is a horizontal, sectional view 70 through a portion of a piece of furniture, for instance the front wall of the center drawer of a pedestal desk showing a lock construction applied in operative position.

Fig. 2 is a front elevation of the construction shown in Fig. 1. 75

Fig. 3 is a horizontal, sectional view similar to Fig. 1 showing the lock replaced by the lock replacing members of this invention.

Fig. 4 is a disassembled perspective view 80 of the filler member and the parts cooperating therewith for retaining it in assembled relation with a suitable piece of furniture.

1 indicates the wall of a suitable piece of furniture which may be the front wall of the central drawer of a pedestal desk constructed of sheet metal or the like. This wall portion 1 is provided with an opening 2 which rotatably receives a handle member 3 provided with a handle 4. This handle member is provided with a cylindrical bore in which is mounted the locking cylinder 5 having the locking cam 6 secured to the flanged portion 7 on the rear end thereof. This locking cam 6 carries a stud 8 in axial alignment 85 with the locking cylinder 5 which projects through an opening in the retaining plate 9. A pin 10 extends transversely to the stud 8 through an opening therein and engages the rear face of the retaining plate 9 for retain- 90 95 100

ing the lock and handle member in assembled relation in the wall 1 of the desk or other furniture, with the flange 11 on the handle member engaging the marginal portion of the wall contiguous to the opening 2. The retaining plate 9 has the opposite end portions secured to the lateral extensions 12 at the opposite ends of the supporting plate generally indicated at 13. This supporting plate 13 has offset portions 14, to which the ends 12 are connected, secured to the wall 1 of the furniture, while the central portion of this plate is offset relative to the portions 14 as indicated at 15. This central portion 15 is provided with a semi-cylindrical opening extending upwardly from the lower edge as indicated at 16, and the locking recess 17 for receiving the bolt 18 of lock 5. This bolt as shown in Fig. 1 is adapted to be projected laterally from the locking cylinder through suitable key operation in the usual manner. This locking cylinder 5 with the mechanism for projecting and retracting the bolt 18 may be of any well known type of construction adapted for the purpose. The locking cam 6 is adapted to provide locking cooperation with the parts of the furniture to be locked relative to the wall 1, or to operate any other desired locking mechanism, to lock doors, drawers, or other desired parts of a desk or other furniture in closed position.

Where it is desired to dispense with the locking mechanism above described for the purpose of illustration, it is found necessary to provide some means of eliminating the objectionable appearance caused by removing the handle member and locking cylinder from the opening 2. This invention provides for eliminating this objectionable feature where it is not desired to use a lock, by means of the insertion of the filler or lock replacing member 20 into the opening 2 in the wall 1 as shown in Fig. 3 of the drawing. This filler member 20 has an annular flange 21 which engages the marginal portion of the wall 1 around the opening, this member having a shape similar to that of the assembled handle member and lock as shown in Figs. 1 and 2, but omitting the handle 4. This filler member is preferably formed of hollow cast material having a cylindrical flange 22 and the axial projection 23 from the rear side which is provided with a threaded socket for receiving the screw member 24. This screw member is adapted to extend through the opening 25 in the plate 26 for retaining the filler member and plate in assembled relation. This plate member 26 is adapted to have the ends engaged with the end portions of central portion 15 of supporting member 13, the plate member 26 extending across the opening 16 in said central portion and serving to retain the filler member in place. The screw 24 can be adjusted to apply the desired tension in assembling the filler member and re-

taining plate 26 together on the supporting member and wall 1, so as to rigidly retain the filler member with the flange 21 engaged with the wall so that the opening 2 is obscured and a finished, neat appearance provided outwardly of the desk or other furniture construction, provided for receiving a lock and where this lock is eliminated.

With this use of the filler or lock replacing member, metal desk constructions or other metal furniture can be made from one set of dies or other equivalent method of construction and constructed for use with or without locks as may be desired by those purchasing and using such furniture. The cost of supplying the filler members with the retaining plates and set screws effects a substantial saving over the construction of two types of desks using two sets of dies, and in addition provide uniformity in the construction of all furniture, making it adaptable for the use of locks whenever it may be desired as may often be the case. The furniture is also adapted for interchanging of locks from one desk to another that it may subsequently be desired to have equipped with a lock.

This invention therefore provides a novel combination using parts of the lock supporting mechanism in cooperation with the retaining elements for the filler or lock replacing member, in providing for the elimination of lock constructions in furniture, with the elimination of the disadvantages which would normally occur from the removal of the locks.

What is claimed is:

1. In combination, a drawer for furniture formed with a lock receiving opening in the front wall, a lock supporting member mounted inside of said drawer and having a portion in the rear of said opening spaced from the front wall, a filler member removably mounted in said opening and formed with an annular flange engaging the marginal portion of the front wall adjacent said opening, a plate member having the ends engaging said lock supporting member, and means adjustably connecting the plate member and filler member for retaining said filler member in said opening.

2. In combination, a piece of furniture having a lock receiving opening formed in one wall thereof, a lock supporting member mounted on the wall adjacent and in the rear of said opening, and means engaging said lock supporting member in the marginal portion of the wall around said opening for filling said opening.

3. In combination, a furniture construction having a lock receiving opening in one wall, a filler member inserted in said opening having an annular flange engaging the marginal portion around said opening at the outside thereof, and means engaging said member and the inside of said

wall for retaining said member in said opening.

4. In combination, a furniture construction having one wall formed with a lock receiving opening, a filler member inserted in said opening having an annular flange engaging the wall around the margin of the opening, a projection on said filler member having a socket in the end thereof, a retaining plate, and a member adjustably engaged in said socket connected to said retaining plate for retaining said filler member in said opening.

5. In combination, a piece of furniture having a lock receiving opening formed in one wall thereof, a lock supporting member mounted on said wall in the rear of said opening, a closure member for the opening in said wall, and means engaging said closure member and lock supporting member for retaining said closure member in said opening.
